SURFACE-INDICATOR.

Specification of Letters Patent.

Patented May 26, 1914.

Application filed January 4, 1912. Serial No. 669,518.

To all whom it may concern:

Be it known that I, JOHN W. GHEEN, a citizen of the United States, residing at Los Angeles, in the county of Los Angeles and State of California, have invented a new and useful Surface-Indicator, of which the following is a specification.

My invention relates to improvements in mechanical instruments for registering in an actual and in an exaggerated form the inaccuracies of a surface, either by moving the instrument over the surface, or by moving the surface under the instrument.

The object of my improvement is first to provide a simple instrument, having levers each receiving the pressure close to the pivoted end and imparting the same at or near the other end, in order to greatly exaggerate the movement given to the lever; second, to provide a means whereby the instrument may be set at any angle; third, to provide a means to protect the instrument from injury when the inaccuracy of the surface is greater than the registering capacity of the instrument; fourth, to provide a means whereby the instrument may be changed from indicating the exaggerated form to the actual inaccuracy of the surface. I attain these objects by means of the mechanism, illustrated in the accompanying drawing, in which

Figure 1 is a plan view of the instrument, having the side plate removed and part of the shank broken away. Fig. 2 is a top view of the same. Figs. 3, 4 and 5 are detail views.

The housing for the spring and levers comprises the back-plate *a* having the boss *b* extending outwardly at its center, (said back-plate being wider at the top than at the bottom and the upper face being the segment of a circle,) the flange *c* extending forwardly from the edge of the back-plate all the way around and the cap-plate *d* fitting against the flange *c* parallel with the back-plate *a*; so as to form a space between the plates *a* and *d* to receive the levers and spring.

The shank *A* is adapted to fit in an ordinary tool post of the lathe or machine upon which the indicator is to be used. The head *H* fits against the end of the shank *A* to form a continuation thereof and the pintle *e* extends from the head *H* into the shank *A*, there being an annular groove in the periphery of the pintle to receive the spring

pressed plug *f*, so that when the pintle has been inserted into the shank *A*, it may freely rotate but cannot be withdrawn, said plug *f* serving as a latch. The spring *E* presses against the plug *f* and the pressure of the spring is adjusted by a screw *g*. A second plug *h* is pressed against the pintle *e* by the spring *E'*, held in place by the screw *i*. The object of the springs *E* and *E'* pressing against the plugs *f* and *h* is to create sufficient tension upon the head *H* to hold the housing from turning except when desired. The stub shaft *j* extends from the boss *b* through the spring casing *k* formed in the head *H* and a rivet *l* (*e*) extends from the end face of the stub shaft *j* through the head *H* at the bottom of the spring casing *k* and the spring *H'* is inserted in the spring casing around the stub shaft between the boss *b* and the bottom of the spring casing to make a tension upon the housing.

The scale *K* is formed upon the segmental top of the housing, said scale being graduated both ways from the center mark and there being a slot between the scale *K* and the cap-plate *d*.

The lever *P* is mounted upon the pivot *F* in the housing and the contact point *B* extends from the upper end of the lever freely through the flange *c* and the contact point *B'* extends from the lower end of the lever freely through the flange *c*, said contact points *B* and *B'* being equal distances from the pivot *F*. The contact point *B* is intended to operate against work in a lathe or against the flat surface of work in a shaper or planer, while the contact point *B'* is intended to operate against the inner surface of hollow work. A second lever *I* is pivoted in the housing at *F'*, the short end of the lever *I* engaging the lever *P*. A third lever *J* is pivoted in the housing at *F''* and is provided with a pin *G* adapted to bear against the lever *I*. A fourth lever *L* is pivoted in the housing *F* and is provided with a pin *G'* bearing against the lever *J* and with the indicator point *L'* at its upper end. The ratio of the leverage between the contact points *B* and *B'* and the indicator *L'* is such that a variation in the surface felt by either contact point will be greatly exaggerated. The graduations upon the scale *K* are intended to show variations of one-thousandth of an inch in the contact points. The spring *O* is fixed in the housing to engage the fourth lever *L* and throw

it to the left. The slide T is mounted in a slot in the flange c. The lever S is pivotally mounted upon the lever P by the pivot P' and a flat spring Y presses against the pin Y' on the lever and holds the lever S normally out of use. The slide T is held normally out of use by the coil spring X seated in the aperture in the flange c and pressing on a ball which lies in a shallow pocket in the slide T. The pin T' extends from the lever S so that when the slide T is moved downwardly the pin T' will engage the lever L and make a direct connection between the lever L and the indicator L'; so as to show the surface variations without exaggeration.

The shank A may be made hollow to receive the center point W or a similar tool.

The object of the friction connection between the head H and the shank A and between the head H and the housing is to provide means for holding the indicator in any adjusted position without the use of set-screws or the like and to provide means which will give way when the pressure is too great, as when the irregularities of the surface are beyond the limits of the vibration of the indicator L'.

In the operation of the indicator the contact point is placed against the surface of the work and the shank A adjusted in the tool post until the indicator point L' is at the center of the scale K so that in moving the contact point over the surface of the work the indicator point may move both ways from the center of the scale K.

I wish to call especial attention to the fact that the contact point B and the indicator point L' move in the same direction, whereas in some other indicators they move in opposite directions, causing confusion to the operator. The contact points B and B' are rigid upon the lever P and equal distances from the pivot F. In effect the lever P is a straight lever as distinguished from a bell-crank lever and the pressure against the contact point B or against the contact point B' in the operation of the indicator is never toward the pivot F but is at angles thereto.

What I claim and desire to secure by Letters Patent is—

1. In a surface indicator, a hollow shank; a head fitting against the end of the shank and having a pintle extending into the shank; means for holding the pintle in the shank and forming friction; a housing fitting against the head; means for holding the housing against the head and forming friction so that the housing may rotate relative to the head and the head may rotate relative to the shank; and indicating mechanism carried by the head.

2. In a surface indicator, a housing having a scale thereon at one end; a lever centrally pivoted in the housing; a contact point carried by one end of the lever and extending through the housing near its scale end; a second contact point carried by the other end of the lever and extending through the unscaled end of the housing at substantially right angles to the first contact point; a lever having an indicator point adapted for movement over the scale, and connections between said levers whereby said indicator point is caused to move in the same direction as the first mentioned contact point.

3. In a surface indicator, a housing; a lever centrally pivoted in the housing; a contact point extending from each end of the lever through the housing, said points being substantially at right angles to each other; a lever having an indicator point extending through the housing; and a system of levers connecting the lever having the indicator point to the lever carrying the contact points, so that movements of the contact points will be greatly exaggerated upon the scale.

4. In a surface indicator, a housing having a scale thereon; a lever centrally pivoted in the housing; a contact point extending from each end of the lever through the housing, said points being substantially at right angles to each other; a lever having an indicator point extending through the housing and adapted to move over the scale; connections between said last named lever and the lever carrying the contact points whereby the movements of the contact points are greatly exaggerated upon the scale; and means for making such a connection between said levers whereby the lever carrying the contact points actuates the lever having the indicator point without such exaggeration.

5. In a surface indicator, a hollow shank; a head fitting against the end of the hollow shank and having a pintle extending into the shank; means for holding the pintle in the shank and causing friction; a housing having a pintle extending into the head at right angles to the pintle in the shank; and means for exerting pressure between the housing and head, so that the housing may be angularly adjusted and held in its adjusted position.

In witness whereof, I have hereunto affixed my signature in the presence of two witnesses.

JOHN W. GHEEN.
